CLAIM

The ornamental design for a sanitary article, as shown and described.

DESCRIPTION

FIG. 1 is a perspective view of a sanitary article according to my new design.

FIG. 2 is a top plan view thereof.

FIG. 3 is a right side perspective view thereof, the left side perspective view being a mirror image of FIG. 3.

FIG. 4 is a right side view thereof, in an outstretched position, the left side view being a mirror image of FIG. 4; and,

FIG. 5 is a rear view thereof, in an outstretched position, the front view being a mirror image of FIG. 5.
